United States Patent Office.

EDWARD WRIGHT, OF WORCESTER, MASSACHUSETTS.

Letters Patent No. 99,511, dated February 1, 1870.

IMPROVEMENT IN SELF-ACTING MULES FOR SPINNING.

The Schedule referred to in these Letters Patent and making part of the same.

To all whom it may concern:

Be it known that I, EDWARD WRIGHT, of the city and county of Worcester, and Commonwealth of Massachusetts, have invented certain new and useful Improvements in Self-Operating Mules; and I do hereby declare that the following is a full, clear, and exact description of the same, reference being had to the accompanying drawings, forming a part of this specification, in which—

Figure 1 represents a view of the front of my improved self-operating mule;

Figure 2 represents a view of the back of my improved self-operating mule;

Figure 3 represents a transverse section on line A B of fig. 1;

Figure 4 represents a section on line C D, fig. 3, giving a view from the front;

Figure 5 represents a section on line E F, fig. 4;

Figure 6 represents a plan view of the machinery beneath the carriage;

Figure 7 represents a side view of the devices for operating the cone-belt lever;

Figure 8 represents a section of the same on line G H, fig. 7.

To enable those skilled in the art to which my invention belongs, to make and use the same, I will proceed to describe it more in detail.

The nature of my invention consists—

First, in the peculiar mechanism employed for varying the speed of the draught-scroll, as hereafter described.

Second, in the peculiar mechanism for regulating and controlling the draught of the yarn, as hereafter described.

Third, in the peculiar mechanism for stopping the carriage when run out to the proper distance to form a stretch, as hereafter explained.

Fourth, in the peculiar devices or mechanism for moving in the carriage sufficient to compensate for the shortening of the yarn during the operation of twisting.

Fifth, in the combination, with the carriage, of a lever for operating the compensating-mechanism, as hereafter explained.

Sixth, in the combination, with the carriage and the compensating-mechanism, of an adjustable lever, as hereafter described.

Seventh, in the peculiar mechanism for operating the catch-dog, which holds the carriage out during the operation of backing off the yarn preparatory to winding up the same.

Eighth, in the peculiar mechanism for operating the winding-faller, substantially as hereafter described.

Ninth, in the combination, with the backing-off slide, of a double switch for throwing the backing-clutch into operation, as hereafter explained.

Tenth, in the combination, with the double switch and the backing-clutch arm, of a centralizing spring, as hereafter described.

Eleventh, in the combination, with the slide for disconnecting the faller-mechanism, of an incline for operating the winding-clutch lever, as hereafter explained.

Twelfth, in the combination, with the carriage, of the slide for disconnecting the faller-mechanism, as hereafter explained.

Thirteenth, in the combination, with the carriage, of the backing-off slide, substantially as and for the purposes described.

Fourteenth, in the combination, with the backing-off slide, of the mechanism for operating the same, as hereafter explained.

Fifteenth, in the combination, with the winding-clutch, of the stationary cords, as hereinafter described.

Sixteenth, in the combination, with the carriage, winding-clutch, and the devices for operating the same, of an adjusting-screw and spring, as hereafter set forth.

Seventeenth, in the peculiar mechanism for throwing the clutches into action for reversing the motion of the carriage, as hereafter described.

In the drawings, the parts marked A indicate the main frame of the machine, and B, the driving-shaft, upon which are arranged the tight pulley C, loose pulley D, and ratchet-pulley E, together with the driving-pulley F, all arranged in the usual manner.

Upon the end of the driving-shaft B is a double pulley, G, from one part of which a belt, a, extends upward to the pulley b, on shaft c, which operates the twist-wheel d, and mechanism connected therewith, which mechanism, being arranged in the ordinary manner, will need no further explanation.

From the other part of the double pulley G, a belt extends to the pulley e, on the end of a shaft, f, by means of which the mechanism of the mule-head is operated. The shaft f is supported and turns in bearings at the upper part of the head-frame H, and it is provided with a cone-pulley, I, from which a belt, g, extends to a corresponding cone-pulley, J, on a central shaft, h, which latter is also arranged in bearings on the frame H, in a similar manner to shaft f, and which has, near its central part, a pinion, i, that meshes into and operates the gear K, upon the main shaft L, as fully indicated in the drawings.

The main shaft L is supported and turns in bearings on the frame H, and upon it are arranged the draught-scrolls M and N, one of which (M) draws the carriage out, and the other (N) draws it in when in operation. The scrolls M and N are made to turn loosely on the main shaft L, but are connected thereto for operation by means of the clutches O and P, one of which (O) is a friction-clutch, and operates the scroll M, while

the other (P) is a toothed clutch, and operates the scroll N. The clutch P is thrown into gear by an upright lever, k, and the clutch O by a similar upright lever, l, both of which are pivoted, at their lower ends, to the bottom part of the frame H, with their upper ends working between pins m m, that project from the back of the slide-bar Q, all of which is fully shown in the drawings.

The scroll M is connected to the carriage by means of two cords, n and p, one (n) being the draught-cord, which passes around a pulley, q, at the front of the machine, and has its end fastened to the lower end of a downward projecting stud, r, at the under side of the carriage-frame R, while the other (p) is attached to the rear side of the carriage-frame, and acts as a steadiers, to prevent a too rapid or unsteady motion when the carriage is moving out.

The belt g is kept taut by a pair of pressure-pulleys, S, attached to the arms of the slide T, and held against the belt g by the pressure of a weight, t, at the end of the stud u, which stud projects backward from the slide T, as shown in the drawings.

The slide T is arranged to move on a rod, V, placed diagonally across the head-frame H, and it is run back and forth by means of a cord, w, fastened at its central part to the stud u, and at one of its ends to the regulating-arm W, while the other end passes over a pulley, z, and has attached to it a weight, X, by means of which the slide T is drawn toward the upper end of the rod V, together with the pressure-pulleys S and band g. The cord w is fastened to the arm W by an eye-bolt, y, which is inserted in one of the holes z, at the upper end of the arm W, as shown in fig. 2 of the drawings.

The lower end of the regulating-arm W is pivoted upon a stud, s, which projects backward from the standard A', and it has arranged near its central part a roll, v, that runs on the edge of the guide-cam B', by means of which the regulating-arm W is operated. The guide-cam is turned, when the carriage is running out, by means of a cord, a', one end of which is attached to a stud, b', beneath the carriage-frame R, the other end being coiled around and fastened to a flanged wheel, c', that is hung and turns on the same stud Y that supports the cam B'.

Attached to the flanged wheel c' is a drum, d', having secured to its circumference one end of a weight-cord, e', which passes over a pulley, f', at the upper part of the frame A, and is furnished at its end with a weight, g', as indicated in the drawings. In the interior of the drum d' is arranged a dog, 1, made as shown in fig. 8 of the drawings, and furnished with a spring, 2, to press the hook part of the dog 1 outward against the shell of the drum d', and thereby cause it to engage with a pin, 3, that projects into the interior of the drum d' from the side of the friction-wheel h', which latter is operated thereby, together with the guide-cam B', which is secured to the outer side of the friction-wheel h', by a screw or bolt, i'. A friction-band, k', is arranged around the wheel h', to prevent it from turning except when forced around by the dog 1. The tension of the friction-band k' may be varied by means of a nut on the tension-bolt l', which bolt is arranged to pass through the stud s.

When the carriage is run out, the cord a' is unwound from the flanged wheel c', thereby causing said wheel, together with the drum d', to revolve in the direction indicated by the arrow, fig. 8.

After the carriage has run out for a certain distance, the hook of dog 1 engages the pin 3, and while the carriage is travelling the remainder of the distance out, the guide-cam B' is caused to make just one complete revolution, thereby swinging the arm W outward and back to its original position, which operation moves the belt g along the cone-pulleys I and J, which increases and diminishes the speed of the latter,

and also the speed of the main shaft L and draughtscroll M, thereby moving the carriage with a greater velocity for a portion of the distance out.

The weight-cord e' is wound upon the drum d' as the carriage is run out, thereby raising the weight g', and as the carriage is run in, the weight g' descends and turns the drum d' and flanged wheel c' back to their former position, winding the cord a' upon the flanged wheel c', while the guide-cam B' remains stationary, it being held by the friction-band k' on the wheel h'.

During the backward motion of the drum d', the pin 3 passes under the point of the dog 1, (which is bevelled off, as shown in fig. 8,) thereby raising it sufficiently to allow of the pin 3 passing freely beneath it without being acted on, while the drum d' is moving backward.

It will be observed, that with this mechanism the motion of the carriage can be perfectly controlled, as a greater or lesser increase of speed can be obtained by simply changing the eye-bolt y to different holes, 2, in the arm W, thereby increasing or diminishing the leverage, and varying the distance to which the band g' is drawn along the cone-pulleys I and J, while the maximum velocity may be obtained when the carriage is at any particular part of the stretch, by making the guide-cam B' of such form that it will swing out the arm W, at the time the carriage passes the given point. Thus it will be seen that the action of the carriage may be regulated so that the mule will spin any quality or kind of wool with equal facility.

At the side of the head-frame H is arranged a perpendicular slide, C', which works up and down in the bearings G, and is provided with a spiral spring, 4, by which it is drawn upward against the stop-pin O', and also with notches n', into which a latch-spring, m', catches, to hold the slide C' in different positions during its operation.

At the upper end of the slide C' is an inclined flange, 5, which operates the slide-bar Q, and levers k and l, which throw the clutches of the draught-scrolls in and out.

A ratchet-bar, D', is pivoted, at p', to the side of the perpendicular slide C', by means of which the latter is moved down, said ratchet D' being operated by a pawl-rod, F', from a crank-plate, G', fastened on the end of the shaft f.

The ratchet-bar D' is pressed forward by a flat spring, q', a lip being formed at the upper end of the ratchet-bar, which strikes against a pin, r', projecting from the side of the slide C', thereby preventing the ratchet-bar D' from being thrown too far forward.

The pawl-rod F' is pressed forward by a flat spring, H', that rests on a pin, s', projecting from the side of the rod F', at its lower end, as fully indicated in the drawings.

The ratchet-bar D' is bevelled off at its front edge, and a rod, I', extending from the shipper-bar J, is arranged through an eye, 7, on the front of frame H, so that when the shipper-bar J is moved, the end of rod I', coming in contact with the bevelled edge of the ratchet-bar D', swings back the latter, causing it to engage with the pawl-rod F', whereby it is moved downward, carrying the slide C', and the parts connected therewith.

A lever, K', pivoted at t' on the frame H, is also arranged to press back the ratchet-bar D'.

To the lower end of lever K' is secured the end of a rod, L', which extends to the front of the machine, where it is supported by the projection u'.

The rod L' has a finger, M', attached to it, against which the stud r strikes as the carriage runs out, and thereby draws forward the lower end of the lever K', and swings back the upper end thereof, in which is arranged a pin, v', that strikes the upper end of the ratchet-bar D', and presses it back, when it will be

moved down by the pawl-rod F' for a distance equal to one notch of the ratchet, thus carrying the end of the ratchet-bar D' below the pin v', when it is again pressed forward by the spring q'.

The rod L' is pressed back, when the carriage is run in, by a coiled wire spring, w', one end of which rests against the projection u', and the other against the hub of the finger M', as indicated in fig. 6.

The finger M' may be adjusted on the rod L' by means of the set-screw X'.

The carriage-frame R is mounted upon grooved travelling-wheels U', in the usual manner, which run on the track-ways N', at the sides of the machine.

At the under side of the carriage-frame R, and supported by the hangers O', is the winding-shaft P', furnished, at its left-hand end, with a pulley, Q', and driven by a belt, R', from the pulley F on the driving-shaft B, which belt R' also drives the cylinder T', and the compensating mechanism.

Upon the winding-shaft P' is arranged a friction-clutch, V', to the inner piece of which is attached the winding-drum W'.

The winding-drum W' is operated as the carriage is moved in or out, by the cords 8 and 9, one end of each being secured to the drum W', while the opposite end of the cord 8 is fastened to a pin, 10, projecting up from one of the bearings 11, which support the worm-shaft 12 and the end of cord 9, being fastened to the upper end of the spring standard 13.

The friction-clutch V' is thrown into and out of gear by an arm, 14, secured to and projecting down from the cross-shaft 15, which shaft is supported transversely to and somewhat above the winding-shaft P' by the hangers 16, beneath the frame R of the carriage.

The spindles a² are mounted upon the frame R of the carriage, and are operated, by bands b², from the cylinder T', in the ordinary manner.

The faller-rods c² and d² are supported by standards e², at the front of the frame R of the carriage, and the fallers f² and g² are held in an elevated position by means of spiral wire springs h², all of which are fully indicated in the drawings.

To the rod c² of the under faller f² is secured a curved arm, 19, the end of which is connected by a rod, 20, to the end of a regulating-spring, 21, fastened to the forward end of the cross-shaft 15.

The rod d² of the upper faller g² is provided with a segment, 22, by means of which it is operated.

The segment 22 is joined, by a cord or chain, 23, to the upper extremity of a perpendicular bar, 24, that moves up and down in bearings 25, on an upright standard, 26, at the front side of the carriage, as shown in the drawings.

Underneath the frame R of the carriage, and arranged to move back and forth, in bearings 27, on the right-hand hanger O', is a backing-off slide, 28, for operating the upper faller g², and for putting into operation the mechanism which backs off the spindles a², preparatory to winding up the yarn.

The backing-off slide 28 is provided with a downward-projecting arm, 29, near its rear end, which is connected by a cord, 30, to the draught-scroll N, and also by a cord or chain, 31, to the periphery of the backing-off clutch 32.

The front end of the slide 28 is made with a perpendicular slotted head, 33, and it also has, near its central part, a switch, 34, for operating the lever 35 of the backing-off clutch.

The switch 34 is made as indicated by dotted lines, fig. 6, so that when the backing-off slide moves forward, the top of the lever 35 passes to the left of the flange of the switch, and when the slide 28 is moved back, the top of lever 35 passes to the right of the flange of the switch, thereby throwing the backing-off clutch into action.

The slide 28 is connected, by means of a rod, 36, to the top of a lever, 37, the lower end of which strikes against a stop-guard, 38, as the carriage is run out, thereby swinging the lever and throwing forward the slide 28, to the position shown in the drawings.

A shackle-bar, 39, is provided with two stud-bolts, 40 and 41, the former being fitted to work in the slotted head 33, and the latter in the slotted projection 42, at the lower front part of the right-hand hanger O'. The stud-bolt 41 projects through the slotted projection 42 sufficiently far to take a bearing upon the cop-builder rail 43, while the stud-bolt 40 projects through the shackle-bar 39 sufficiently far to receive the curved shoulder in the lower end of the swinging arm 44. (See dotted lines, fig. 3.)

The swinging arm 44 is hinged to the perpendicular bar 24, as shown in the same figure.

The cop-builder rail is to be made adjustable, and operated by mechanism in the ordinary manner for building or forming the cops in the common way.

A latch-dog, 45, made in the form of a bell-crank, is pivoted, at 46, to the right-hand hanger O', the horizontal arm of which is provided with a notch at the under side of its front end, to catch upon an adjustable catch-piece, 47, which is secured to the bed-frame 48.

The upright arm of the latch-dog strikes against a pin, 50, which is supported in a piece attached to the right-hand hanger O', thereby retaining the horizontal part in the proper position to engage the catch-piece 47.

As the carriage runs out, the notched end of the latch-dog 45 passes over and beyond the catch-piece 47, for a distance equal in amount to that required to compensate for the shortening of the yarn in twisting, so that the notch at the end of the horizontal arm of the latch-dog 45, comes in contact with and latches on to the catch-piece 47, simultaneously with the slipping of the belt, which stops the twisting, and it remains in that position, holding the carriage during the backing off of the spindles, until the slotted head 33, of the backing-off slide 28, strikes against the upright arm of the latch-dog 45, thereby releasing it from the catch 47, and allowing the carriage to be run in by the draught-scroll N and cord 30.

The lever 35, which operates the backing-off clutch, is held in a perpendicular position by means of a centralizing spring, 51, secured to an arm, which projects from the right-hand hanger O'.

The spring 51 is provided with an angular notch on its under side, that fits on to the top of the lever 35, in such a manner, that when the latter is pressed either to the right or left by the switch 34, it raises the spring 51, and when the switch 34 has passed the lever 35, the latter is immediately returned to a central position by the notch in the spring 51.

Parallel to the backing-off slide 28, and supported in the same bearing therewith, is a slide, 52, for disconnecting the faller-mechanism after the yarn has been wound upon the cops.

The rear end of the slide 52 strikes against a stop-piece, 53, which projects forward from the head-frame H, when the carriage is run in, which throws said slide 52 forward, and the front end thereof pushes the curved shoulder of the swinging arm 44 off from the stud-bolt 40, when the fallers are drawn up by the springs h².

The disconnecting-slide 52 is moved back by the backing-off slide 28, which is provided with a pin, 54, that strikes the swing-piece 55, which latter, coming in contact with a pin, 56, in the side of the disconnecting-slide 52, causes said slide to recede.

An inclined-lug, 57, is formed on the slide 52, which bears down the end of the lever 17, when the slide 52 is moved forward with the carriage, thereby slightly turning the shaft 15, and throwing the winding-clutch V' out of action.

The compensating-mechanism, which moves the car-

riage in to compensate for the shortening of the yarn during the operation of twisting, consists of a rack, 58, mounted on a rocker-frame, 59, that is hinged upon the bed-frame 48.

The rocker is grooved on top, and the rack 58 works back and forth in said groove, it being retained upon the rocker by a screw, 60, that passes through a slot, 61, in the central part of the rack 58.

A pinion, 62, and worm-gear 63, firmly secured together, are arranged on a stud, that projects upward from the bed-frame 48, as shown in the drawings.

The worm-gear 63 is operated by a worm, 64, attached to the worm-shaft 12, said shaft being turned, as before stated, by the belt R' from the driving-pulley F.

The rocker-frame is pressed back by a spring, 65, so that the rack 58 is out of gear while the carriage is being run in. But as the carriage runs out, a lever, 66, which projects downward from the carriage-frame R, comes in contact with the slanting point 67, of the rack 58, and slides it forward to the extent of the slot 61, when it can go no further.

The end of lever 66, which is bevelled off at one side, crowds the point 67 to the left, which swings up the rocker 59, and throws the rack 58 into gear with the pinion 62, whereby the former immediately receives a backward motion, and, by pressing against the end of lever 66, which is caught on the notch at the right-hand side of the point 67, moves the carriage slowly back while the yarn is being twisted.

The lever 66 is pivoted, near its upper end, to a supporting-piece, 68, attached to the inside of the carriage-frame R, and a set-screw, 69, is arranged through said piece 68, by means of which the lever 66 may be adjusted to the proper position.

A spiral wire spring, 70, extends from the top end of the lever 66 to the back part of the carriage-frame R, which spring 70 is to prevent breaking the parts in case their operation is not perfect.

It will be understood that the power of the spring 70 is sufficient to overcome the resistance of the carriage, so that the latter will be moved by the pressure of the rack 58 against the lever 66.

Parallel to the regulating-spring 21, and secured to the front end of the shaft 15, in a similar manner, is a spring, 71, having through its end, a bolt, 74, that extends downward from the frame R of the carriage.

The bolt 74 is provided with a nut at its lower end, beneath the spring 71, and by screwing said nut up or down, the amount of friction on the clutch V is increased or diminished, as the case may be.

The operation is as follows: Commencing when the carriage starts to run out.

The draught-scroll M moves out the carriage, as before stated.

When sufficient roving has run from the rolls, which are arranged on the top of frame A, in the usual manner, to form a stretch, the speed at which the carriage moves is accelerated, for the purpose of stretching the roving, as required.

This accelerating motion is obtained by the regulating-devices and cone-pulleys I and J, in the manner heretofore described.

The carriage runs out until the stud r strikes the finger M' on the rod L', which, acting on the lever K', pushes back the ratchet-bar D', and the latter engages with the pawl-rod F, whereby the perpendicular slide C' is moved down the distance of one ratchet, where it is held by the spring m', which falls into the lower notch n'.

The bar Q, being moved by the inclined flange 5, throws out the clutch O of the draught-scroll M, and stops all further outward motion of the carriage.

The lever 37, striking against the guard 38, throws forward the backing-off slide 28, and the shoulder of the swinging arm 44 locks on to the stud-bolt 40, at

the upper end of the shackle-bar 39. The carriage is gradually run in for a short distance, while the yarn is being twisted, by the compensating-mechanism, as and for the purpose stated.

When the yarn is twisted sufficiently, notice is given by the twist-wheel d, which, being properly adjusted, sets into operation the mechanism that slides the slipper-bar J', and the main belt is thereby shifted from the ratchet-pulley E to the tight pulley C, and the motion of the ratchet-pulley E and driving-pulley F is stopped by suitable mechanism, arranged for that purpose, not shown in the drawings. The end of the rod I' is at the same time brought in contact with the bevelled edge of the ratchet-bar D', thereby throwing the latter into action, and the slide C is moved downward by the pawl-rod F' to the second notch of the ratchet, which allows a moment of time wherein the motion of the spindles a' may wholly cease; and at the next revolution of the shaft f, the slide C is moved down to the third and last notch of the ratchet, when, the bar Q, being moved by the flange 5, operates lever k, and throws in the clutch P of the draught-scroll N, which commences to wind up the cord 30, thereby drawing back the backing-off slide 28, the carriage being meanwhile held in position by the latch-dog 45 and catch-piece 47.

As the slide 28 moves back, the switch 34 throws into action the backing-off clutch 32, which latter, being operated by the cord or chain 31, turns back the winding-shaft P', and backs off the spindle a'. When the switch has passed the lever 35 of the backing-off clutch, the clutch is thrown out by the centralizing spring 51. The top end of the shackle-bar 39 being drawn back, it pushes up the swinging arm 44 and perpendicular bar 24, which, in connection with the segment 22, lowers the upper faller g', whereby the yarn is guided upon the cops.

When the slide 28 is drawn back to nearly its full extent, the slotted head 33 strikes the upright arm of the latch-dog 45, and releases the latter from the catch-piece 47. The disconnecting-slide 52 is also moved back by the pins 54 and 56 and swing-piece 55, thus removing the lug 57 off from the lever 17, which latter is drawn up, and the friction of the winding-clutch thrown into action by the springs 21 and 71.

The slide 28, having been drawn back to its full extent, the force of the draught-scroll N now acts upon the carriage, which is run in thereby, the yarn being at the same time wound upon the cops, by the action of the cords 8 and 9, which turn the winding-drum W, together with the winding-shaft P', cylinder T', and spindles a', as the carriage runs in. When the carriage has run in, and wound up the yarn upon the cops, the end of the disconnecting-slide 52 comes in contact with the stop-piece 53, and disconnects the swing-arm 44 from the stud-bolt 40, in the shackle-bar 39, thereby releasing the fallers, which are drawn up by the springs h'.

The inclined lug 57 runs over the lever 17, and throws out the winding-clutch V', while a suitable arranged stop-dog throws back the slipper-bar J', and shifts the main belt to the ratchet-pulley E, which puts the spindles again into action.

The guard 72 presses out the catch-piece m', and the perpendicular slide C is drawn up by its spring 4, thereby releasing the flange 5 from the bar Q, when the latter, being thrown back by the spring 73, operates the levers h and k, whereby the clutch P of the draught-scroll N is thrown out, and the clutch O of the draught-scroll M is thrown into action, which again runs out the carriage, and the operation is repeated.

Having described my improvements in self-operating mules,

What I claim therein as new, and of my invention, and desire to secure by Letters Patent, is—

1. The combination, with the draught-scroll M and

cone-pulleys I and J, of the friction-clutch O, gears k, and belt g, substantially as and for the purposes set forth.

2. The combination of the regulating-arm W, provided with a series of holes, z, and guide-cam B', with the connecting-cord w and shipping-slide T, substantially as and for the purposes set forth.

3. The combination, with the shipping-slide T, of the diagonal guide-rod V, arranged in relation to the cone-pulleys I and J, substantially as shown in the drawings, whereby the pressure-pulleys S bear upon the band g, at equal distances from their respective cone-pulleys, as the band g is shifted from one end of the pulleys to the other, for the purposes set forth.

4. The combination, with the flanged wheel e¹, drum d¹, and dog 1, of the friction-wheel h¹, friction-band k¹, pin 3, and cam B', substantially as and for the purposes set forth.

5. The combination, with the flanged wheel e¹ and carriage-frame R, of the cord a¹, substantially as and for the purposes set forth.

6. The combination, with the flanged wheel v¹, cord a¹, and carriage-frame R, of the drum d¹, weight-cord e¹, and weight g¹, or equivalent device, as and for the purposes set forth.

7. The combination, with the rod L' and ratchet-bar D', of the lever K', and projection r on the carriage, substantially as and for the purposes set forth.

8. The perpendicular slide-bar C', provided with notches n', substantially as and for the purposes set forth.

9. The combination, with the slide-bar C', of the catch-spring m', substantially as and for the purpose set forth.

10. The combination, with the slide-bar C', of the ratchet-bar D', pawl-rod F', and springs m' and 4, substantially as and for the purposes set forth.

11. The combination, with the perpendicular slide-bar C' and horizontal slide-bar Q, of the inclined flange 5, substantially as and for the purposes set forth.

12. The combination, with the pinion 62, of the rocker 59 and sliding rack 58, substantially as and for the purposes set forth.

13. The combination, with the carriage-frame R, of the adjustable lever 66, substantially as and for the purposes set forth.

14. The combination, with the lever 66, of the adjusting-screw 69 and spring 70, substantially as and for the purposes set forth.

15. The combination, with the carriage-frame R and rocker 59, of the notched and bevelled rack 58 and lever 66, substantially as and for the purposes set forth.

16. The combination of the backing-off slide 28, having the slotted head 33, with the upright arm of the catch-dog 45, as and for the purposes set forth.

17. The combination, with the slotted projection 42, on the right-hand hanger O', and slotted head 33, on the slide 28 of the shackle-bar 39, stud-bolts 40, 41, and swing-arm 44, substantially as and for the purposes set forth.

18. The combination, with the backing-off slide 28, of a double switch, 34, and lever 35, for operating the backing-off clutch, substantially as and for the purposes set forth.

19. The combination, with the double switch 34 and arm or lever 35, of a centralizing spring, 51, substantially as and for the purposes set forth.

20. The combination, with the slide 52, for disconnecting the faller-mechanism, of an inclined lug, 57, for operating the winding clutch-lever 17, substantially as and for the purposes set forth.

21. The combination, with the carriage-frame R, of the slide 52 and arm 53, for disconnecting the faller-mechanism, substantially as shown and described.

22. The combination, with the carriage-frame R, of the backing-off slide 28, substantially as shown and described.

23. The combination, with the backing-off slide 28, of the lever 37 and stop-guard 38, substantially as and for the purposes set forth.

24. The combination, with the backing-off slide 28 and disconnecting-slide 52, of the swing-piece 55, and pins 54 and 56, substantially as and for the purposes set forth.

25. The combination, with the winding-drum W and clutch V', of the cords 8 and 9, substantially as and for the purposes set forth.

26. The combination, with the carriage-frame R, winding-clutch V', and the devices for operating the same, of an adjustable screw or bolt, 74, and spring 71, substantially as and for the purposes set forth.

27. The combination, with the bevelled ratchet-bar D', of the rod I' and slide J', substantially as and for the purposes set forth.

EDWARD WRIGHT.
